UNITED STATES PATENT OFFICE

RICHARD WILLIAMSON, OF CHICAGO, ILLINOIS, ASSIGNOR, BY MESNE ASSIGNMENTS, TO BEARDSLEE CHANDELIER MANUFACTURING CO., OF CHICAGO, ILLINOIS, A CORPORATION OF DELAWARE

LIGHTING FIXTURE

Application filed June 14, 1928. Serial No. 285,445.

This invention relates to lighting fixtures and its object is to provide a neat and attractive fixture of simple construction adapted to receive a lamp and to soften and distribute the light therefrom in a highly efficient manner to produce a superior illuminating effect.

The invention is capable of embodiment in shades which vary in detail construction and shape and in the accompanying drawings I have shown the invention in several selected embodiments as follows:

Fig. 1 is a sectional elevation showing a flared shade having an open top and an opening in its bottom.

Fig. 2 is similar to Fig. 1 showing a shade provided with a crowned top.

Fig. 3 is similar to Fig. 2 showing the shade open at the top and provided with a flat bottom closure.

Fig. 4 is similar to Fig. 3 except that the bottom is concavo convex.

Fig. 5 is similar to Fig. 3 with the shade provided with a crowned top closure.

Fig. 6 is similar to Fig. 5 except that the bottom is concavo convex.

Fig. 7 is a sectional view showing a cylindrical shade having a flat top closure and a concavo convex bottom closure.

Fig. 8 is a sectional view showing a cylindrical shade open at the top and bottom.

The invention will be usually embodied in a fixture comprising a plurality of arms adapted to be suspended from the ceiling of a dining room and above a table, or from the ceiling of a living room, but I do not restrict the invention to this or any other particular type of fixture because it will be readily appreciated, as the invention is better understood, that it is capable of embodiment in other fixtures with satisfactory results.

Therefore, I consider it sufficient to show and describe the arm 9 of the fixture in a general way only as provided with a bracket 10 for supporting the lamp socket 11 to which it is securely fastened. This socket may project horizontally above the arm and sufficiently close to the arm so that the lamp 12 will project through a side opening in the shade and close to an opening 13 in the arm, Fig. 1.

The shade is generally cylindrical in shape,

its side wall extending from top to bottom all around the shade, and this side wall may be flared as shown in the shades of Figs. 1 to 6, or it may be straight as shown in the shades of Figs. 7, 8. The flared shade 14 of Fig. 1 has an open top 14' and an open bottom 14"; and the bottom preferably has an inwardly directed rim 15 about the opening 14". The flared shade 16 of Fig. 2 has an open bottom 14" and a rim 15 like Fig. 1 and it also has a crowned top 16'. The shade 17 of Fig. 3 has an open top like the shade 14 of Fig. 1, but it has a flat closed bottom 17'. The shade 18 of Fig. 4 is similar to the shade 17 of Fig. 3 except that its closed bottom 18' is concavo-convex and fits in the opening 13 of the arm. The shade 19 of Fig. 5 is similar to the shade 17 of Fig. 3 except that it has a crowned top 19'. The shade 20 of Fig. 6 is similar to the shade 19 of Fig. 5 except that it has a concavo-convex bottom 20'. The shade 21 of Fig. 7 has a straight side wall, a closed top 21' and a concavo-convex bottom 21". The shade 22 of Fig. 8 is also straight sided and it has an open top 22' and an open bottom 22".

Every form of the shade is provided with an enclosed opening 24 in its side wall located adjacent the bottom of the shade to receive the lamp. The side wall extends from the top of this opening to the top of the shade in the flared or straight cylindrical forms illustrated.

The opening 13 may be located close to the rim 23 of the arm, Fig. 1, or it may be spaced from the rim, Fig. 2. In either construction, the shade may be removed easily for cleaning or for other purposes, and replaced without necessitating removal of the lamp.

It is desirable that the socket should not be exposed to view from below the fixture. In some fixtures it may be hidden by the arm, which is usually of ornamental design, but in some cases it may be desirable to lower the socket close to the arm and incline the lamp as shown in Fig. 3 for better concealing the socket.

The construction and arrangement of the arm, the shade and the lamp provide for the

distribution of the light from the lamp in a superior manner giving a soft and evenly distributed illumination which is highly effective especially with a ceiling fixture. The shade will throw a flood-like effect upward which is softened by the provision of a top. The shade will soften and distribute the light laterally and, if the wall of the shade is flared, the light will be distributed laterally and downwardly. If the shade is provided with a concavo-convex bottom, as I prefer, the light will be thrown downward in a manner highly desirable and satisfactory for illuminating a table, for reading and for other purposes. In all constructions, the light from the lamp will be softened and distributed in a manner which will avoid shadows and will produce the most efficient lighting effect.

20 I have shown the invention in a simple form with the shade made to receive a single lamp, but the shade may be enlarged to receive a plurality of lamps and the opening 13 may be enlarged or may be duplicated to 25 accommodate a plurality of lamps. The shade may be made of translucent glass with or without decorations, or it may be made of any other material, and any desired shape within the scope of the following claim:

30 I claim:
In a lighting fixture, the combination of a horizontally disposed supporting arm provided with a bottom opening and having a seat portion surrounding said opening, a 35 glass shade having a bottom wall removably supported on said seat portion and an upstanding wall surrounding said bottom wall, said upstanding wall having an enclosed side opening adjacent the bottom wall, a socket 40 mounted on said arm outside of said shade and a lamp mounted in said socket and extending substantially horizontally into said shade through said side opening and adjacent said bottom wall.
